HEAT DISTRIBUTION SYSTEM FOR TOBACCO CURING BARNS

John A. Maul and Philip Kaftol, Brooklyn, N. Y., assignees to American Machine and Foundry Company, a corporation of New Jersey

Application September 27, 1950, Serial No. 186,972.

8 Claims. (Cl. 263—19)

This invention relates to tobacco curing apparatus and more particularly to a heat distribution apparatus which is used with a jet type burner.

After harvesting tobacco leaves it is the practise to hang the leaves in a tobacco curing barn where they are dried and cured by means of artificial heat. Due to advancements made in the direct fired oil burning art, it has now become possible to so completely oxidize the fuel that the combustion gases can be discharged directly into the tobacco curing barn using only one burner without any danger of contaminating the tobacco leaves with carbon or oil smudge. This has the advantage that less costly equipment is required to cure tobacco, fuel is more efficiently utilized and less heat is dissipated to the outside atmosphere.

Such a burner releases considerable heat and to be practical this heat must be distributed in such a way that it can be effectively employed in the curing barn without becoming a fire hazard.

It is therefore an object of this invention to provide a distribution apparatus which is economical to construct and which will stand up under the maximum temperatures and thermal shock which are encountered.

Another object is to provide a material for a heat distribution apparatus which will have sufficient thermal insulation to lower the surface temperature of the apparatus to such a degree that combustible material such as tobacco leaves coming into contact with the distribution apparatus will not ignite.

It is also an object of the present invention to provide an improved heat distribution system which can be easily assembled in a tobacco barn and which permits the distribution apparatus to be readily packaged for shipment.

Another object of this invention is to provide a material out of which distributing ducts can be made which is light in weight so as to decrease shipping costs and which can withstand high temperatures which are encountered in jet type burners.

Another object is to provide a heat distribution apparatus, the main components of which are of similar construction and are adaptable for nesting together so that they can be easily packaged for shipment.

A further object is to provide heat distribution apparatus which will have sufficient heat retaining ability to prevent short cycling of the burner.

Another object is to provide sufficient mechanical strength in the apparatus so that it can withstand occasional abuse as it might receive in a tobacco barn.

Another object is to provide sufficient flexibility in the system so that the heat on one side of the barn can be readily increased or decreased to compensate for uneven distribution of tobacco in the barn as well as to effects attributable to weather and the heat insulating ability provided by the walls of the barn itself.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is an isometric view of the improved heat distributing apparatus,

Fig. 2 is a cross-sectional end elevation taken on the line 2—2 of Figure 1 showing the heat distributing header in cross-section,

2

Fig. 3 is a cross-sectional end elevation of a distributing arm before clamping.

Fig. 4 is a cross-sectional end elevation taken on line 4—4 of Figure 1 of the same distributing arm showing the unit after clamping.

Fig. 5 is an isometric view of a modified form of the heat distribution apparatus.

The heat distributing apparatus shown in Figure 1 is well suited for use with jet type burners of the type 10 having high temperatures such as that shown and described in copending patent application Serial Number 179,710, filed on August 16, 1950, by Henry A. Oldenkamp, now Patent 2,673,726.

In the arrangement used to illustrate the invention 15 the heat distributing apparatus comprises a fire box or chamber C, a header designated generally by the letter H and heat distributing arms A. While this particular arrangement of the header and arms have been found to be very satisfactory it is evident that in some installations it may be desired to modify them by making the arrangement a modification of a U, I, X or O shape instead of the T- and L-shaped arrangement shown in the present embodiment.

The fire box or chamber C receives the hot combustion gases from the jet burner B. Since there is considerable heat in such combustion gases this chamber must be able to stand up under high operating temperatures. It has been found that while fire brick and fire clay stand up satisfactorily it is not always feasible to transport them for small jobs. Vermiculite concrete on the other hand has been found by applicants to be more readily adaptable for such use. This material can be cast in sections which are readily transportable. They are also relatively light in weight and can stand up in transportation and use under high temperatures and may be quickly assembled on the job into a fire box.

The header H comprises an inverted U-shaped tunnel made up of two sections 10 and 12 and a bottom section 30, as shown in cross section in Fig. 2. Arms A extend outwardly from the header H to distribute the hot combustion gases received therefrom. The header H and the arms A are also constructed of a suitable refractory material such as vermiculite.

While the exact ingredients of the vermiculite concrete may be varied as desired as in mixing sand, cement and cinders, it has been found satisfactory for example to use one part of cement and four parts of vermiculite aggregate to make the sections of which the header H and arms A are made. In addition the concrete may, if desired, be aged or cured by artificial heat.

To assist in reinforcing each component section, suitable reinforcing metal, such as expanded metal 14 may be mounted in each section as it is made. Suitable anchors 16 and 18 are placed in the vermiculite at the time it is poured to provide projecting lugs 20 and 22 through which a suitable clamp 24 can be inserted to draw both sections together at their upper end. These sections may also be made with a slight taper 26 and 28 at their upper end so that when the clamp bolt 24 is tightened it will cause the bottom of the U-shaped sections to spread out.

The bottom portion of the header H consists of a vermiculite plate 30 which has ridges 32 and 34 extending upwardly along each side upon which the upper section is designed to be supported. The bottom plate 30 may also be reinforced by suitable reinforcing iron 36, such as expanded sheet metal. At the time the vermiculite is cast or poured into the form, suitable lugs 38 and 40 are incorporated into the concrete so as to form projecting members 42 and 44 against which the two half shells 10 and 12 can engage at their lower end, when the clamp bolt 24 is tightened so as to spread apart the lower ends of the housing.

A plurality of arms A extend at right angles from the header H. The arms A are connected to the header H by means of a suitable elbow joint L or T joint T. The arms are made up of two half sections of the same type of material as the headers 10 and 12. Since heat travels along the top of the arms, it is possible to leave the bottom portion of the arms open where the arms are hori-

zontally arranged. The sections 10 and 12, making up the arms A are supported on suitable spaced rails 46 and 48 such as angle iron. The angle irons 46 and 48 are joined together by spacing cross bars 50, and are supported in elevated position on suitable supports 52 such as brick or cement blocks.

Each pair of half sections comprising the inverted U-shaped housing arms A are separated from each other lengthwise along the rails 46 and 48. The distance each pair of half sections are separated from each other are progressively increased as the distance from the header H increases. This permits heat to escape through the joints out into the tobacco barn uniformly across the entire barn. Where an uneven distribution of heat is desired so as to compensate for special conditions such as wind, uneven loading of the barn, etc. the joint spacings can be increased. This will release more heat on this side of the barn than on the other side. It will thus be appreciated that this heat distribution apparatus is highly adaptable to a drying condition found in different tobacco curing barns.

In some cases it may be desirable to assist the gases in passing from the header H through the distributing arms A by having the arm A mounted at an inclined angle from the header H. In this case the bottom portion of the arm is preferably maintained closed so as to confine the heat therein and to allow it to escape through the spaced joints between each section. This will result in an even distribution of hot gases along the entire length of the arm. This adaptation of the arm also increases the flow of hot gases through the arm, thereby permitting this arrangement to also be used for compensating for varying conditions in the tobacco barn.

A suitable wire netting or screen 54 is placed over each joint and at the ends of the arms to assist in the dissipation of heat escaping through the joints and to prevent falling tobacco or other combustible material from coming in contact with the hot gases.

The header H is supported on a similar pair of rails 56 which are spaced from each other by bars 58 in the same manner as is done by bars 50 to maintain the rails 46 at a fixed distance with respect to each other.

The hot combustion gases are delivered from the jet type burner B, located on the outside of the tobacco curing barn, into the fire box C. The fire box or chamber C as previously stated is made of a suitable refractory material to receive the hot gases from the burner B and deliver them to the header H. As previously mentioned the fire box C can be made of fire brick or a vermiculite concrete such as the header H and distributing arms A are made of or a combination thereof. The type of direct fired burner referred to in this application may be similar in design and construction to that shown and described in the copending application Serial Number 179,710 previously referred to therein.

In the modified form of our invention we have disclosed how the heat distribution system shown in Figure 5 may be made in the form of flat blocks 76 consisting of a suitable heat resisting material such as vermiculite concrete. The blocks may be nailed together by nail 78 or may be screwed together by suitable screws. By forming one side of the edge of the distributing arms with a slight taper it will cause the lower portion of the flat blocks to expand outwardly against the side rails 80 and 82, when the flat blocks are fastened together by nails or lag screws 78. As in the preferred form of the invention the distributing arms are open at their bottom but the header is enclosed on all sides. Each joint of the distributing arm is slightly separated. The amount of separation is varied depending on where heat is desired and generally the amount of separation is increased, the greater the distance the joint is from the header.

In those cases where the distributing arms are mounted at an inclined angle to facilitate hot gases moving therethrough the underportion of the arms are enclosed so as to prevent the hot gases from escaping therefrom. The joints between the sections making up the distributing arms are separated however in the manner just described so as to permit the hot gases to escape from the arms through these separations.

The operation of the heat distribution apparatus may be briefly described as follows:

Fuel oil is delivered to the burner B from a suitable source (not shown). The burner B discharges the combustion gases into the fire box C where they are com-

pletely oxidized and from where they escape into the header H. The gases are pushed from the header H into the distributing arms A. In moving through the distributing arms A the gases tend to rise to the upper end of the inverted U-shaped arms. In passing from section to section a certain amount of gas escapes through each joint until at the end of the arms all the remaining gas escapes. Any falling leaves will be kept out of dangerous contact with the hot gases by the screens 54.

It will be noted that applicant's apparatus enables a direct fired jet burner to be effectively used for curing tobacco because he has devised a heat distributing arrangement which is capable of evenly distributing heat received from a single source at high temperatures across the entire bottom of the tobacco curing barn.

The present invention discloses how the cost of curing tobacco can be materially reduced by utilizing all the heat of the combustion gases by permitting them to be discharged into the tobacco curing barn directly and providing a suitable type of material which will not melt or deteriorate when subjected to the heat of a direct fired jet type burner.

The present heat distribution system is of such practical design and construction that it can be readily shipped to farmers in the field at reasonable cost because of its lightness in weight and because it may be stored compactly for shipment. It is also sufficiently rugged to withstand normal abuse such as individuals standing thereon.

Vermiculite concrete has been found to have such characteristics that it is capable of storing heat so that when the jet fired burner shuts off the vermiculite heat distributing apparatus will continue to radiate heat into the tobacco barn and thereby decreasing the frequency of operation of the burner.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. A tobacco curing barn heat distributing apparatus for use with a jet fired burner comprising, a fire box made of refractory material for receiving the hot combustion gases from the jet fired burner, ducts made of a refractory material and connected to said fire box for leading the hot combustion gases away from said fire box, and distributing arms connected to said ducts and extending transversely to said ducts, said arms comprising a pair of rails fixed in a position above the floor and a plurality of substantially inverted U-shaped members of vermiculite concrete resting on said rails, each of said U-shaped members being spaced from the adjacent U-shaped members to allow hot gases to pass upwardly at spaced intervals along the arms, and each of said U-shaped members being made from a plurality of sections of vermiculite concrete.

2. A heat distributing apparatus for use with a jet fired burner comprising a fire box made of refractory material into which hot combustion gases from a jet burner are discharged, tubular members made of a refractory material extending outwardly from said fire box from which the hot combustion gases received from the fire box are conducted away from the fire box, and heat distributing arms connected to said tubular members and extending substantially transversely from said members, said arms comprising a pair of rails fixed in a position above the floor and a plurality of arm sections made from an assembly of vermiculite concrete components connected to said tubular members and resting on said rails, each of said arms having a longitudinal opening formed along its lower length to conduct hot gases away from said tubular members across the floor of a tobacco curing barn.

3. A distribution system for use with a direct fired jet type burner comprising a hollow header for receiving hot combustion gases from said burner, distributing arms connected to said header and extending transversely with respect to said header, said arms having a pair of rails fixed in a position above the floor and a plurality of inverted substantially U-shaped sections made up of two elongated walls of vermiculite concrete joined together along their upper sides and having the lower portion of their length resting on said rails, each of said

U-shaped sections being spaced from the adjacent U-shaped section to allow hot gases to pass upwardly at spaced intervals along said arms.

4. In a tobacco curing barn, apparatus for distributing hot combustion gases received from a single source of supply, said apparatus comprising, a combustion gas receiving chamber, ducts made of vermiculite extending outwardly from said chamber for conducting hot combustion gases away therefrom, angle iron supports positioned at right angles to said ducts, sections of vermiculite supported on their edges on said rails and having their opposite edges beveled so that when the beveled edges are clamped together they cause the lower edge of each section to expand outwardly against said rails, said clamped sections being spaced from one another to allow gases being moved therethrough to escape through said spacings, and clamps for holding the upper edges of said sections together.

5. A heat distribution system for a tobacco curing barn comprising a fuel burner, a fire box made of refractory material for receiving the hot combustion gases from the burner, a header made of refractory material and connected to the fire box for leading the hot combustion gases away from the fire box, angle irons extending substantially transversely from said header, elongated vermiculite duct sections supported along their elongated edges on said angle irons for distributing the hot combustion gases received from said header across the floor of a tobacco curing barn, each of said sections being made from a plurality of components and means for clamping the components of said sections together to force the lower sides of said sections outwardly against said rails, said vermiculite ducts being made of sections spaced linearly from one another to permit heat to escape through said spacings, a source of hot combustion gases and means coating with said vermiculite ducts for moving said hot combustion gases through said vermiculite ducts.

6. A heat distribution apparatus for use with an intermittently operated fuel burner in a tobacco curing barn comprising a combustion chamber into which said burner discharges hot combustion gases, ducts made of refractory material for conducting the hot combustion gases away from said combustion chamber, arms made from sections of hollow reinforced vermiculite concrete connected to said ducts for conducting gases received therefrom across the floor of a tobacco curing barn, said sections being of a thickness adequate to store heat absorbed from the combustion gases and to radiate heat therefrom

when hot combustion gases are not delivered to said sections, and means for supporting the segments making up said arms at separated distances from one another to allow hot combustion gases being conducted through said arms to escape through said separations.

7. A tobacco curing apparatus comprising a combustion chamber for receiving hot combustion gases, ducts extending outwardly from said combustion chamber, flat slabs of vermiculite concrete secured together along their edges to form individual duct sections for conducting hot combustion gases across the floor of a tobacco curing barn, rails extending transversely from said ducts for supporting said individual duct sections at a distance spaced from the floor of a tobacco curing barn, said sections being spaced from one another to allow a portion of the hot combustion gases to escape through each of said spacings and means coating with said duct sections for moving said hot combustion gases through said ducts and said duct sections.
- 10 8. Apparatus for distributing heat across the bottom of a tobacco barn comprising a main duct, spaced rails having upwardly extending flanges positioned across the floor of a tobacco barn and positioned transversely with respect to said main duct, ducts consisting of pairs of elongated vermiculite sections of inverted substantially U-shaped cross-section supported along their edges on said rails, the adjoining edges of said sections being oppositely beveled so that the lower edges move against said rails when the adjoining edges of said sections are bolted together, said sections being spaced lengthwise from one another to allow hot combustion gases to escape through said spacings and means for bolting the adjoining edges of said sections together.
